UNITED STATES PATENT OFFICE

2,575,318

MERCURY SWITCH.

Raymond P. Mattern, Minneapolis, Minn., assignor to Minneapolis-Honeywell Regulator Company, Minneapolis, Minn., a corporation of Delaware

Application January 8, 1948, Serial No. 1,126

6 Claims. (Cl. 200—152)

1

My invention relates to an electric switch of the type having a liquid contact circuit closer for controlling the flow of current therethrough, and more particularly to the mounting structure for the circuit closer.

It is therefore an object of this invention to provide an improved construction and arrangement in a switch of this type.

Other objects and advantages will become apparent with the reading of the following specification and drawings wherein:

Figure 1 is a plan view of the preferred embodiment of this invention;

Figure 2 is a side elevation view of the switch shown in Figure 1; and

Figure 3 is a cross-sectional view of the liquid contact circuit closer included in the preferred embodiment of the switch.

Figure 4 is a sectional view of the switch taken along lines 4—4 of Figure 1.

As is seen in the drawings, my invention is shown applied to a switch incorporating a rotatable liquid contact circuit controller which is commonly known as a rotary metal mercury switch. Such a switch can be seen in my Patent Numbers 2,260,745, dated October 28, 1941, and 2,342,354, dated February 22, 1944, which are assigned to the same assignee as the present invention. The electric switch 10 generally disclosed in Figures 1 and 2 of the drawing comprises a liquid contact circuit controller 11 positioned in an insulated switch housing 12 and mounted for rotation therein, to provide a manually operated wall switch of the toggle type.

The liquid contact circuit controller 11, or rotary metal mercury switch, is composed of metallic cup-like electrodes 13, 14 telescopically interfitted and separated by ceramic partition or baffle 15 which has an aperture 16 therethrough to permit contact of the mercury bodies 17 separated by the baffle and complete the circuit therethrough. An insulating asbestos washer 20 further separates electrodes 13, 14, and a glass seal or fill 21 between the electrode members, seals the insulating washer 20 and the ceramic in position while adhering to the electrode members to provide an airtight seal for the container. Metal mercury switch 11 contains a hydrogen atmosphere with the mercury fill 11, as is conventional in mercury switches. Indent 22 in electrode 13 of the circuit closer 11 is provided in the manufacture of the switch for the purpose of evacuating and sealing the same and is utilized herein, as will be hereafter described, as a means of mounting the switch.

2

The switch housing 12 is a box like casing structure with a switch receiving recess 23 open at the front. The housing 12 is made of an insulating material, such as molded plastic, and is generally rectangular with the exception of two extending boss portions 23, 24 wherein the conductive members 25, 26 are mounted to the switch housing 12. Switch housing 12 includes on its inner surface an inwardly projecting boss portion 27 which is shaped on its inner surface to conform with the surface of electrode 14 of switch 11. The boss 27 provides a flat bearing surface engaging the flat end of switch electrode 14 and a cylindrical bearing surface engaging a cylindrical surface of electrode 14. These surfaces locate the switch 11 in the housing 12. A conductor 25 attached to boss portion 23 of switch casing 12, such as by screw 30, is made of a good electrical conductive material and is bent to project into the recess 23 of switch housing 12 with its free extremity curved to conform with and engage the cup-like electrode 14 of switch 11. The conductor 25 is flexible and is shaped to engage the electrode 14 and bias the switch 11 into engagement with the cylindrical bearing surface of boss 27 which is curved to conform with electrode 14 of liquid contact circuit closer 11. Since the entire portion of the cup-like electrodes 13, 14 are made of the good electrical conductive material, electrical contact is made by engagement of conductor 25 with electrode 14. A conductor 26, attached at one extremity to boss portion 24 of switch housing 12 in a suitable manner, such as by screw 30, extends into the recess 23 of switch housing 12 and is bent to engage electrode 13 of circuit closer 11. The conductor 26 is provided intermediate its ends with a projecting knob portion 32 curved to conform to and adapted to coat with the indent 22 in electrode 13 of switch 11. The free extremity 33 of the conductor 26 engages a surface of the wall of switch housing 12 insuring definite positioning of circuit closer 11 within switch housing 12. Electrical contact is made through engagement of knob portion 32 and indent 22 in a ball and socket connection which further provides for pivoting of circuit closer 11 about its axis and centering of the same, such that it is biased into engagement with the opposite wall of switch housing 12 and is held therefor rotation by projecting boss portion 27 and conductor 25 about its axis. The function of conductor 26 is to bias the switch 11 in a direction normal to the operation or bias of conductor 25 providing for a simple yet positive positioning

of the switch with good electrical contact therethrough.

Cemented to circuit closer 11 is handle portion 34 which provides the means of rotating circuit closer 11 about its axis. A mounting strap or bracket 35 is provided to mount switch 10 in the usual wall box. It is attached to switch housing 12 at lug portions 36 thereon and is provided with opening 37 through which handle 34 extends. Bracket 35 also contains mounting holes 40 therein to facilitate mounting.

Switch 10 is operated by movement of handle 34 from an off to an on position to establish an electrical circuit through the conductor members and the switch 11 mounted therebetween. The switch is centered for rotation about its axis by conductors 25, 26 and boss portion 27. At the same time a good electrical contact is established with the electrodes of the switch which is not affected by rotation thereof. The outwardly extending boss portions 23, 24 of switch housing 12 are fabricated so that external wires, or connections, not shown, can easily be connected to the conductors at mounting screws 38, 39. As is shown in Figure 2, movement of handle 34 rotates circuit closer 11 in such a manner that aperture 16 in ceramic baffle 15 is moved above or below the level of mercury in circuit closer 11. In this manner contact is either made or broken between the two pools of mercury positioned on either side of baffle 15.

The mounting structure described above provides a simple and effective way of positively engaging a rotary type metal mercury switch to prevent lost motion and to provide good electrical contact through the switch. This type of structure eliminates the necessity of biasing the switch and handle to predetermined operating positions since frictional engagement of the electrodes of the switch with the conductors and the engaging portions of the switch housing maintain the switch in the position desired.

In considering this invention it should be kept in mind that the present disclosure is intended to be illustrative only and the scope of the invention is to be determined only by the appended claims.

I claim:

1. A switch comprising, a casing member having a switch receiving recess and a boss portion integral therewith projecting into said recess, a rotatably operable mercury switch having two electrodes one of which electrode has a detent, a flexible connector member attached at one extremity to said casing member and having a curved portion conforming to one electrode of said switch making electrical contact therewith, said connector member biasing said switch into engagement with said boss portion, a second flexible electrode secured at one extremity to said casing member and having a projecting knob near its opposite extremity adapted to coact with said detent in said switch electrode making electrical contact therewith, said second named connector member biasing said switch in the direction of said boss and said first named connector member in a plane normal to the operation of said first named connector, said boss and said connector members cooperating to establish a stationary axis of rotation for said switch prohibiting axial movement of said switch while permitting rotational movement about said axis, and means operatively connected to said switch for rotating the same about said stationary axis.

2. A device of the class described, in combination, a switch, a casing member having a recess adapted to receive said switch, a boss integral with said casing member extending into said recess with its inwardly extending extremity adapted to conform to said switch, a flexible member attached at one extremity to said casing and shaped to conform to and frictionally engage said switch biasing it in a direction of engagement with said boss, and a second flexible member attached at one extremity to said casing member and adapted to engage said switch biasing it in a direction normal to the direction of operation of said first named flexible member, said boss and said flexible members cooperating to establish a stationary axis of rotation for said switch while prohibiting axial movement thereof but permitting rotation of said switch about said stationary axis.

3. In a device of the class described, the combination of a switch casing member having a switch receiving recess, a switch, a boss portion on said casing member adapted to engage said switch, a flexible member secured to said casing and adapted to engage and bias said switch into engagement with said boss portion of said casing member, and a second flexible member secured to said casing and adapted to engage said switch biasing the same in a direction normal to the operation of said first named flexible member, said switch being adapted to be frictionally engaged by said flexible members and slidably rotated about a stationary axis determined by said flexible members and said boss while being held against axial movement.

4. In a device of the class described, the combination of a casing member having a switch receiving recess, a switch having conductors thereon, a boss portion included in said casing member and adapted to engage said switch, a flexible member secured to said casing and adapted to engage and bias said switch into engagement with said boss portion of said casing member, and a second flexible member secured to said casing and adapted to engage said switch biasing the same in a direction normal to the operation of said first named flexible member, said first and second flexible members being made of electrically conductive material and providing electrical connections to said switch conductors, said boss portion and said flexible members cooperating to establish a stationary axis of rotation for said switch permitting rotation thereon while prohibiting axial movement of said switch.

5. In a switch of the class described, the combination of an insulated casing member having a switch receiving recess and a switch with a plurality of electrodes positioned therein, a boss portion integral with said casing member extending into said recess and adapted to be engaged by said switch, a flexible connector member of electrical conductive material secured at one extremity to said casing member and frictionally contacting an electrode of said switch biasing said switch into engagement with said boss portion, a second flexible connector member of electrical conductive material secured at one extremity to said casing member and adapted to frictionally engage another electrode of said switch biasing said switch in a direction normal to the operation of said first named connector member, said boss portion and said flexible connector members defining with said switch a stationary axis of rotation about which said switch is adapted to be

rotated while being mounted to prohibit axial movement thereof.

6. In a device of the class described, in combination, a casing member having a switch receiving recess therein with an aperture leading thereto, a boss portion integral with said casing member having a semicircular surface thereon projecting into said recess, a rotatably operative mercury switch having two cylindrically shaped electrodes one electrode of which has a 10 detent therein, said switch being positioned within said recess of said casing member with one of the electrodes abutting said semicircular surface of said boss portion, a flexible connector member attached at one extremity to said casing member and having a curved portion conforming to and engaging said one of said electrodes of said switch remote from and diametrically opposite said boss and making electrical contact therewith, said connector member biasing said switch into engagement with said boss, a second flexible electrode member secured at one extremity to said casing member and having a projecting knob near its opposite extremity adapted to engage the detent in the other of said electrodes making electrical contact therewith, said second connector member biasing said switch in the direction of said boss and said first named connector member in a plane normal to the operation of said first

named connector member, said boss and said connector members cooperating to establish a stationary axis of rotation for said switch prohibiting axial movement thereof while permitting rotational movement of said switch about said stationary axis, and handle means of insulating material attached to said switch extending out of said recess in said switch casing through said aperture.
